UNITED STATES PATENT OFFICE.

JOHN D. NEWLAND, OF LOS ANGELES, CALIFORNIA.

DESIGN FOR A COMBINATION LAMP AND CLOCK CASE.

Application filed February 14, 1927. Serial No. 20,764. Term of patent 14 years.

To all whom it may concern:

Be it known that I, JOHN D. NEWLAND, a Canadian citizen, and a subject of the King of Great Britain, now residing at Los Angeles, in the county of Los Angeles and State of California, have invented a new, original, and ornamental Design for Combination Lamp and Clock Cases, of which the following is a specification, reference being had to the accompanying drawing, forming part thereof.

Figs. 1 and 2, are respectively front and side elevation of combination lamp and clock case showing my new design.

Fig. 3 is a plan view of same.

I claim:

The ornamental design for a combination lamp and clock case as shown.

JOHN D. NEWLAND.
